FRANK J. OMO, OF FORT WORTH, TEXAS

AIR COMPRESSOR

Application filed October 12, 1929. Serial No. 399,114.

This invention relates to improvements in air compressors and more particularly relates to an improved construction of opposed piston compressors and apparatus for reciprocating the pistons.

One of the objects of this invention is to provide an air compressor structure wherein the volume of air compressed at each stroke will be substantially doubled without increasing the weight or size of the compressor.

Another object of this invention is to provide an opposed piston air compressor whereby the full energy of the opposed pistons will be available for compressing air.

Another object of this invention is to provide an improved construction of opposed piston motor adapted as an air compressor whereby greater volumes of air may be compressed with the same amount of energy, due to the reduction of the reciprocating losses, and the increased size of the compression chamber.

Another object of this invention is to provide an opposed piston type air compressor having a greater cooling area and having more effectively driven opposed pistons.

Another object of this invention is to provide a novel means for transmitting the rotating energy of a crank shaft to an opposed piston type air compressor whereby the cam mechanism is adapted to occupy a minimum space and which is of a more simplified construction.

Another object of this invention is to provide a poppet and sleeve valve, opposed piston, air compressor having a simplified piston operating structure which is more efficient in use, has fewer parts, and in which friction losses have been reduced to a minimum.

Further objects and advantages of this invention will appear from the following description thereof, taken in connection with the attached drawings, which illustrate a preferred form of embodiment of single cylinder air compressor according to my invention, and in which,

Fig. 1 is a side elevation of the air compressor having parts broken away to show the internal construction thereof.

Fig. 2 is a central section of the compressor.

Fig. 3 is a detail section on the line 3—3 of Fig. 1.

Fig. 4 is a detail section substantially on line 4—4 of Fig. 2.

Double acting compressors for air and other gases have been used heretofore, but in the prior constructions, either duplicate cylinders operated from a central shaft or a common cylinder having pistons operated from separate spaced shafts have been used. The valve mechanism has been extremely complicated and such pumps have been in more or less disfavor. Those disadvantages are obviated in the present construction.

The air compressor 10 shown to illustrate my improved form of construction comprises a crank case 12 having the lower removable portion 13 and the cylinder 14 secured thereto; an upper piston head 16 connected to the sleeve 18 and the lower piston head 22 reciprocate within the cylinder 14 in opposed relation. The sleeve 18 extends substantially the length of the cylinder and the integral arms 18a project into the crank case to cooperate with the wrist pin 20 near the bottom of the crank case. The opposed piston 22 reciprocates within the sleeve 18 and is driven from the connecting rods 32 by the driving pin 24 in the skirt of the piston and is rotated to oppose the compression of the upper piston head. The crank shaft 26 is provided with a cam 28, known as a Cassinian oval having opposed concave sides 28a and substantially circular ends 28b. Cam rollers 31 journaled on intermediate link pins 30, cooperate with the sides of the cam 28 and are joined by links 32 to the wrist pins 20 and 24. A roller 34 is supported on the wrist pin 24 and a similar roller 36 is journaled on the wrist pin 20. The rollers 34 and 36 cooperate with the sides of the cam 28 in such manner that the rollers are always in contact at diametrically opposed positions on the cam; similarly with the rollers 31, which are always in contact with the cam 28 at opposed positions, depending on the number of cylinders and number of cam rollers. The center line of the rollers 31

60

is always perpendicular to the rollers 34 and 36.

When the crank shaft 26 is rotated from the position shown in Fig. 2, the opposed pistons 16 and 22 will separate as the circular portions 28b of the cam 28 recede from the rollers 34 and 36 and force the rollers 31 further apart. At a maximum position the circular portions 28b of this cam will then 10 be spaced between the rollers 31 and the resulting compression chamber will be at its maximum volume.

No valves are required, for when the piston head 16 is moved to its maximum outward position, the port 40 in the sleeve 18 will be closed and out of communication with the cooperating port 42 in the cylinder 14. On this outward stroke a vacuum being created by the receding movement of the opposed cylinder outward and the opposite cylinder downward, the spring loaded poppet valve 44 will open, permitting the air to pass into the compression chamber 46. No other valve mechanism is required. When 20 the maximum outward stroke is reached and the crank shaft continues to turn, the curved portion 28b of the cam will then recede from the roller 31 and proceed toward the rollers 34 and 36 respectively. The links 32 maintain the contact of the four rollers on the cam and while the cam is receding from two of the rollers other portions of the cam are in contact with the remaining two rollers to reciprocate the pistons. When the head 16 starts its downward movement the vacuum condition in the chamber 46 ceases, the poppet valve 44 automatically closes and the air is compressed between the upper cylinder head 16 and the lower piston head 22, which are 30 now moving toward each other. Meantime the head 16 having moved downward due to the action of the cams and the sleeve 18, the port 40 in the sleeve 18 comes into cooperation with the port 42 in the cylinder 14 as clearly 40 shown in Fig. 2, and the compressed air will rush from the cylinder into the manifold 48 to the discharge conduit 50.

As shown in Fig. 3 the wrist pin 20 passes thru the roller 36 and four links 32 are provided which project upwardly to the wrist pins 30—pairs of the links being parallel to each other and projecting upward on either side of the cam 28. Trunnions 52 are secured on the projecting ends of the wrist pin 20 and are guided in guides 54 fixed in the crank case on each side of the central roller 36 so that the roller 36 will move upward and downward in a straight line directly below the pistons.

Means to cool the cylinder is provided by the fins 60 on the outer surface of the cylinder 14 which insure sufficient radiation of the heat to permit the compressor to work at normal temperatures. The manifold 48 may also be constructed to radiate heat rap-

idly, and as the cylinder is open at the top, the rapid movement of the air through the open top aids to cooling it.

Adjacent the manifold 48 and in the reciprocating piston sleeve 18 are two piston rings 70 19 to prevent the loss of compression adjacent the manifold. Piston rings may also be provided in the piston 22 to prevent leaks and escape of the compressed gases.

In operation the rotation of the crank shaft will cause reciprocation of the piston 22 and cylinder head 16 in opposed directions, the head and piston periodically separating and coming substantially together, alternately draw in a charge of gas, compress 80 it, and discharge the compressed gas. As the pistons separate the air rushes in past the poppet valve 44, and when the head 16 reaches the outer end of its stroke, the poppet valve will close and the compression begins. 85

As the rollers are always in contact with the surface of the cam, and as the link mechanism positively positions each of the rollers, it will be obvious that upon rotation of the driving shaft that the opposed pistons will 90 be positively reciprocated. The links maintain a parallelogram shape as the opposite sides are always parallel and a continuous reciprocating motion can be had by the rotation of the cam within the center of the 95 parallelogram. It is of course possible to vary the shape of the cam surface to bring about different rates of movement of the pistons as for example: it may be desirable to provide for rapid motion near the end of the 100 stroke and a relatively slower motion of the pistons as they reach the inner compressed position as the compression at that time requires the greatest force per unit distance of movement.

It is also to be noted that by extending the sleeve of upper cylinder head, downward below the crankshaft and projecting the skirt of the piston downward to the crank-shaft, it is possible to have a common compression chamber and also have a common crank or driving shaft to reciprocate both piston and cylinder head simultaneously. This reduces the number of working parts and provides for increased compression. 110

It is also obvious that with the same volume of compression chamber, it is only necessary to have one half the stroke as both the cylinder head and piston move. The saving in friction and wear is apparent.

The Cassinian oval cam is also of considerable advantage over the usual crank shaft and pitman arrangement as the stresses on the driving shaft are balanced by the contact of the four rollers at once on the cam. There 125 are no sudden power impulses and the device will run smooth and quiet. This is particularly true due to the absence of complicated valve mechanism, but one poppet valve which works automatically and a sleeve valve 130

being provided. This also saves considerable energy.

With the present construction, the greatest amount of energy is directly converted into compression of the gases and in view of the opposed relation of the pistons, both outward and inward, power losses are reduced to a minimum. This pump is particularly desirable for air compression as it is provided 10 with cooling fins and an open cylinder, and as it has few working parts, it is well adapted for continuous, rugged work.

While I have shown a preferred form of embodiment of this invention, I am aware 15 that other modifications may be made, and I therefore desire a broad interpretation of the claims within the scope and spirit of the invention and limited only by the claims appended hereinafter.

20 I claim:

1. In an air compressor of the class described, a cylinder, opposed pistons adapted to reciprocate in said cylinder, a driving shaft, a cam secured to said shaft, anti-friction rollers carried by each of the pistons and bearing upon the cam at substantially diametrically opposite points and linkage between the rollers to positively hold all of said rollers in contact with said cam.
2. In an air compressor of the opposed piston type having a pair of operative pistons, one of said pistons reciprocating in the other piston, a driving shaft, a driving cam secured to said shaft, an anti-friction member carried by each of the pistons and each anti-friction member bearing upon the cam at substantially diametrically opposite points and means engaging the cam and operatively connected to said anti-friction members to force said members to engage said cam at all times.

3. In an air compressor of the class described, a cylinder, a crank case, opposed pistons operatively reciprocated within said cylinder, shafts carried by the pistons and intersected by the axes of the latter, rollers mounted on the shafts, a power shaft, a cam secured to the power shaft and bearing at substantially diametrically opposite points upon said rollers, and a guide in said crank case, one of said piston shafts reciprocating therein.

4. In an air compressor of the opposed piston type, a pair of pistons, one of said pistons having a skirt forming a compression chamber with the other piston, rollers carried by the pistons, additional rollers linked to said first rollers, a cam having a Cassinian oval shape, the first of said rollers and the second of said rollers bearing at diametrically opposite points upon said cam, said second rollers engaging said cam at substantially right angles to said first rollers, and a driving shaft secured to said cam and adapted to reciprocate said pistons.

5. In an air compressor of the class described, a cylinder, opposed pistons within said cylinder and means to reciprocate said pistons, said pistons having arm extensions, a shaft operatively connected to said extensions, a roller mounted on said shaft, a driving shaft extending thru one of said pistons and between some of the arms of the latter and a cam mounted on said driving shaft engaging said roller and movable between the other arms of the piston.

6. In an air compressor of the class described a piston having guide trunnions, stationary guideways in which said trunnions operate and an anti-friction member carried 80 by the piston a cam engaging said anti-friction member and a power shaft to which the cam is secured.

7. In an air compressor of the class described, a stationary cylinder, stationary guideways arranged parallel to the axis of said cylinder, a piston cooperating with the cylinder, guide members on the piston engaging said guideways, a roller carried by the piston, a cam engaging said roller and a driving shaft upon which the cam is mounted.

8. In an air compressor a stationary cylinder, stationary guideways arranged parallel to the axis of the cylinder, oppositely projecting guide members carried by the piston and 95 slideable in said guideways, an anti-friction member carried by the piston, a cam engaging said anti-friction member at a point substantially in line with the axis of the piston and a driving shaft on which the cam is mounted.

9. In an opposed piston type air compressor, a stationary cylinder, a plurality of pistons cooperating with the cylinder, a driving shaft, a cam fast on said shaft, rollers on said pistons, said rollers cooperating with said cam and adapted to be reciprocated by it.

10. In a gas compressor of the opposed piston type, a crank case, a cylinder secured to said crank case, a reciprocating piston within said cylinder, a sleeve adapted to receive and reciprocate said piston, a driving shaft, said sleeve extending beyond said driving shaft, a second reciprocating piston mounted within said sleeve and cam means adapted to reciprocate said pistons simultaneously away from and toward each other, and means to introduce a gas and means to remove the compressed gas.

11. In a gas compressor of the class described, a cylinder a plurality of pistons actuated within said cylinder, one of said pistons adapted to be reciprocated within the other piston, one of said pistons having a driving sleeve extending thruout the length of said cylinder, a cam cooperating with the end of said sleeve and secured to a driving shaft to reciprocate said piston, said piston automatically opening to permit inflow of 125 gas therethrough.

12. In a gas compressor of the class described a crank case, a driving shaft mounted in said crank case, a cylinder secured to said crank case, opposed pistons adapted to reciprocated within said cylinder, a driving sleeve secured to the upper piston and extending below the driving shaft, anti-friction rollers secured in the skirt of one of said pistons and in the end of the driving sleeve of the other piston, a cam secured to said driving shaft adapted to contact with said rollers at diametrically opposite points and additional means adapted to maintain the rollers in contact with said cam at all times.
13. An opposed piston type gas compressor having an open cylinder in which said opposed pistons are reciprocated, said cylinder being provided with a compressed gas manifold, an automatically opening intake mechanism, cooling fins on the surface of said cylinder and a parallelogram linkage secured to said opposed pistons and adapted to be varied in shape to reciprocate said pistons and to separate said pistons the maximum amount on intake and to simultaneously force said pistons together for compression.
- In testimony whereof I have affixed my signature to this specification.
